WRAPPING MACHINE

Arthur Marion Raney, Corpus Christi, Tex., assignor of twenty-four per cent to George J. Fulton, Nueces County, Tex.

Application September 8, 1939, Serial No. 294,014

3 Claims. (Cl. 93—2)

This invention aims to provide a simple but effective means whereby, when a wet bottle is rolled, the bottle will be caused to pick-up a wrapper of tissue paper or the like. The invention aims to provide novel means for presenting the paper to the bottle, and for causing the bottle to wrap itself in the paper.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Fig. 1 is a side elevation;

Fig. 2 is a top plan;

Fig. 3 is a section on the line 3—3 of Fig. 2;

Fig. 4 is a section on the line 4—4 of Fig. 1;

Fig. 5 is a section on the line 5—5 of Fig. 1; and

Fig. 6 is a section on the line 6—6 of Fig. 1.

The device forming the subject matter of this application may be made out of any desired material or combination of materials. It includes a box-like support 1, which may be open at the bottom, to the extent shown in the drawings. The front end of the support 1 is marked by the letter A, and the rear end of the support is marked by the letter B. At its rear end, the support 1 is provided with a downwardly and rearwardly inclined top 2, terminating short of the forward end of the support, to form an opening 3. Downwardly and rearwardly inclined racks 4 are secured to the side walls of the support 1, within the support, and the ends of a movable or shiftable sustaining rod 5 are received adjustably in the racks 4.

Within the support 1 is disposed a paper tray 6, which rests on the rod 5. At its rear end, and at its bottom, the paper tray 6 has a tubular socket 7 which receives a pivot rod 8, detachably mounted in the side walls of the support 1, the pivot rod being provided at one end with a rectangular head 9 adapted to be engaged detachably with a spring keeper 10 on one side wall of the support 1, externally thereof. The tissue paper 11 which is to be wrapped around a bottle 12, is mounted in a stack on the bottom of the paper

tray 6. The rear end wall 14 of the paper tray 6 has a forward inclination at an acute angle to the bottom of the tray, to keep the forward end of the stack 11 of paper positioned properly with respect to the bottle, when the bottle is in the dotted line position of Fig. 3, it being noted that the bottom of the tray 6 has a downward inclination toward the rear end of the support 1. The tray 6 is open at its forward end. As the stack 11 of paper is used away, the tray 6 can be raised, by shifting the rod 5 upwardly and forwardly in the racks 4 and, thus, the uppermost sheet of paper always is in a position to be engaged by the bottle that is to be rolled. Since the bottom of the support 1 is open, the operator 15 can shift the sustaining rod 5 readily, without taking the machine apart.

The numeral 15 marks a bottle holder disposed within the support 1 and extended upwardly, out of the opening 3. The bottle holder 15, at its forward end, has a short top wall 16, and, spaced from the top wall 16, the bottle holder has a longer top wall 17 that is connected to the forward edge of the top 2 of the support 1 by a hinge mechanism 18. Between the inner edges of the walls 16 and 17 there is an opening 19, the sides of the bottle holder 15 having notches or seats 20 to receive the bottle that is to be wrapped. The wall 17 of the bottle holder 15 is provided at its forward edge with a rounded bead 21, over which the paper from the stack 11 can be dragged, by the rolling bottle, without tearing the paper.

At a point near its rear end, the top wall 17 of the bottle holder carries angle brackets 22, the depending portions of which form crank arms. To the aforesaid crank arms are connected the rear ends of pull springs 23, the pull springs extending backwardly and downwardly, and having their forward ends connected to the lower portion of the support 1.

The operator places the bottle 12 in the seats 20 of the bottle holder 15, and presses the bottle and the bottle holder down until the bottle, which is wet from the refrigerator, comes into contact with the uppermost sheet on the stack 11. The bottle then is rolled backwardly and downwardly along a flexible waterproof strip 24, made of rubber or the like, and secured to the top 2 of the support 1, and to the upper or top wall 17 of the bottle holder 15. The paper, being engaged at one end with the bottle 12, is pulled off the stack 11, over the bead 21, and the bottle is wrapped. As soon as the bottle holder 15 is freed from downward pressure, the bottle holder rises to the position of Fig. 3, to

receive another bottle, under the action of the springs 23.

The device is simple in construction, but will be found thoroughly advantageous for the ends in view.

Having thus described the invention, what is claimed is:

1. A bottle wrapping machine comprising a support, a paper tray carried by the support, a bottle holder mounted on the support at one end of the tray and above the tray, for vertical movement with respect to the tray, and means for sustaining the holder yieldably.

2. A bottle wrapping machine comprising a support, a paper tray hinged in the support for vertical adjustment, means for holding the tray in vertically adjusted positions, a bottle holder

mounted on the support at one end of the tray and above the tray, for vertical movement with respect to the tray, and means for sustaining the holder yieldably.

3. A bottle wrapping machine comprising a support, a tray carried by the support, a bottle holder mounted on the support at one end of the tray and above the tray, for vertical movement with respect to the tray, and means for sustaining the holder yieldably, a portion of the top of the holder, and a portion of the top of the support constituting a bottle runway, and one edge of said portion of the holder forming a guide, over which paper from the tray is drawn, as the bottle moves along the runway. 15

ARTHUR MARION RANEY.
